INDIVIDUAL CREAMER

William V. Doyle, Chicago, Ill.

Application October 30, 1945, Serial No. 625,489

5 Claims. (CL. 65—31)

1

The present invention relates to an individual creamer and especially to a novel construction of container for cream or the like adapted to be associated and carried with any cup and saucer without danger of spilling the contents of the creamer.

Among the objects of the present invention is to provide a novel construction of creamer which is so constructed, arranged and designed as to be approximately wedge-shaped and to substantially conform to the shape or contour of any cup and saucer with which it is used. Difficulty has been experienced with individual creamers of the type now employed in that these members are so designed and constructed that they must either be carried separately from the cup and saucer and thus make it impossible for a waitress or person serving to carry these articles in one hand, or they are carried in such a position that they are unstable and easily tipped and the contents spilled.

It is, therefore, an important object of the present invention to provide a novel individual creamer having substantially the shape of a wedge so that when it is placed in position, is wedged into the space between the cup and saucer and held securely in position by virtue of this wedged position and gravity.

It is a further object of the present invention to provide an individual creamer receptacle which is so constructed and arranged as to prevent the contents from being spilled when placed upon the saucer, plate or similar support. This is accomplished by making the creamer receptacle of such contour that when it is filled and placed upon the saucer, plate or the like, the contents thereof are disposed below the upper lip of the creamer.

Further objects are to provide a construction of maximum simplicity, efficiency, economy and ease of assembly and operation, and such further objects, advantages and capabilities as will later more fully appear and are inherently possessed thereby.

The invention further resides in the construction, combination and arrangement of parts illustrated in the accompanying drawings, and while there is shown therein a preferred embodiment, it is to be understood that the same is susceptible of modification and change, and comprehends other details, arrangements of parts, features and constructions without departing from the spirit of the invention.

In the drawings:

Figure 1 is a view in perspective of a coffee,

2

tea, or other cup and saucer provided with a novel individual creamer.

Figure 2 is a view in vertical cross-section through the cup, saucer and individual creamer and showing the position of the creamer and the level of the contents thereof when placed upon the saucer.

Figure 3 is a view similar to Figure 2 but disclosing another and important form of creamer which is of universal application and shown mounted in position upon a cup and saucer. This form is especially adapted to fit any cup and saucer combination.

Figure 4 is a view in vertical cross-section showing the creamer of Figure 3 in position for filling and further showing it filled a predetermined amount.

Figure 5 is a view similar to Figures 2 and 3, but showing a further alternate construction of individual creamer or receptacle.

Figure 6 shows two creamers or receptacles of the type shown in Figure 5 in nested relation and filled for use.

Referring more particularly to the disclosure in the drawings, the novel embodiment shown in Figures 1 and 2 comprises a saucer 1 and cup 2 of the type employed in serving coffee, tea, or the like. Mounted upon this saucer and conforming substantially to the contour thereof and to that of the curved side of the cup, is an individual creamer or receptacle 3 having its inner side wall 4 so dished or concaved as to substantially conform to the exterior of the side wall 5 of the cup. The rear or outer wall 6 of the creamer or receptacle may be suitably contoured in any manner as to substantially conform to the edge of the saucer, while the base 7 is shown flat or substantially flat but may be provided with a recess or depression 9 adapted to receive the annular lip or rim 10 of the outwardly and upwardly flared side wall 8 of the saucer. This stabilizes the position of the creamer or receptacle and prevents accidental or unintentional displacement thereof as the cup and saucer are carried by the waitress or server. Although the recess is preferably arcuate, it may have any contour that will receive the edge of the saucer, but due to the substantially wedge shape formed by the side 4 and base 7, the creamer or receptacle will normally be securely held without such recess, or by employing such a recess, the side wall need not necessarily contact the cup but the receptacle may be retained on any saucer, plate or the like and with or without a cup, bowl or the like.

The base 7 of the creamer is preferably sub-

stantially flat so that when it is removed from the cup and saucer to be filled with cream or the like, it may be placed and retained in an upright position during the filling operation. The upper edge 11 when in the position to be filled, is inclined toward the rear face 6 thereof so that the creamer may be filled only to the level 12 and when mounted upon the saucer in Figure 2 the upper level of the contents is disposed below the upper edge 11 of the creamer and this upper edge is in a substantially horizontal plane.

Figures 3 and 4 disclose another and highly important construction of creamer or receptacle 13 that may be employed with any combination of saucer or plate 14 and cup or bowl 15, whereas that shown in Figures 1 and 2 is preferably made and used as part of a saucer and cup combination in which the creamer substantially conforms to the contour of the cup. In this latter form of invention shown in Figures 3 and 4, the rear wall 16 of the creamer or receptacle may be formed in substantial accordance with the disclosure in Figures 1 and 4, although it may be rounded or of any other configuration. The wall 17 is preferably inclined as shown rather than concaved as in Figure 1, but due to the wedge-shape formed by this side wall 17 and the base 18, the creamer or receptacle will be securely retained on the saucer or plate by reason of its wedge-shape and gravity without danger of displacement.

In Figures 5 and 6 is disclosed another form of creamer or receptacle 19 having a side wall 20 and base 21 similar to those of the device of Figures 3 and 4, but in which the rear wall is provided with an inclined portion 22 disposed at approximately the same angle as the side wall 20, and a substantially vertical portion 23. By making the creamer or receptacle with the inclined portion 22, they may be nested together when placed on a table, tray or other substantially horizontal support for filling, carrying, storage or other purpose. Furthermore, it may be preferable to insert a weight or the like 24 in the wedge-shaped corner or angle to give these receptacles greater stability when placed on such a horizontal surface. This weight may be of lead or any other heavy metal or material suitable for the purpose.

It will be readily appreciated that the individual creamer or receptacle shown in the drawings may be so contoured as to very closely approximate the shape of the cup and saucer as in Figures 1 and 2, although for universal application, I prefer the forms shown in Figures 3, 4, 5 and 6 which may be used with approximately any shape of cup or bowl and saucer or plate now on the market and form a unique assembly therewith. The creamer or receptacle may also be made of various kinds of material, either like that of the cups or bowls and saucers or plates with which it is to be used or in contrasting colors or materials depending upon the individual taste.

It will be readily seen that the novel creamers, jugs or receptacles being of substantially wedge-shape, and especially the form shown in Figures 5 and 6, they may be nested together for convenience in filling, storing, shipping or for carrying where a number of these creamers are carried on a tray.

From the above description and the disclosure in the drawings, it will be appreciated that the present invention eliminates the inherent dis-

advantages of individual creamers or receptacles now employed, is easily carried and obviates any danger of spillage of the contents as each is firmly held when placed in the position shown in Figures 1, 2, 3 and 5, thus permitting the waitress or server to carry the cup, saucer and creamer or receptacle in one hand and with security. In this connection it should be noted that the creamer or receptacle substantially conforms to the edge of the saucer or plate, although it may be contoured in virtually any fashion, while the base of the creamer or receptacle may be tilted at a considerable angle without danger of spillage. For this reason, it may be employed with a very deep saucer or plate as well as with a saucer or plate that has but little concavity.

Although the present invention has been disclosed as relating primarily to a creamer, this receptacle may be employed for serving various forms of a flowing or fluid mass, such as syrup, sugar or the like, and may be used with a plate, bowl or any combination thereof. This receptacle may be used in serving cream with a bowl of cereal, syrup for a plate of pancakes or waffles, etc. In that case, the receptacle would preferably be provided with a recess or depression for receiving the annular lip of the plate.

Having thus disclosed my invention, I claim:

1. An individual creamer comprising a container for use with a cup having an upwardly and outwardly flaring side wall and a concave saucer having an outwardly and upwardly projecting rim spaced outwardly from the cup, said container being open at the top and having connected side walls and a base supported on the rim of the saucer, one of said side walls being upwardly and outwardly inclined from and at an acute angle with respect to the base and substantially conforming to the upwardly and outwardly flaring side wall of the cup whereby the creamer, when placed on the saucer with the upwardly and outwardly inclined side wall of the container in contact with the adjacent side wall of the cup, is held securely upon the rim and wedged between it and the adjacent side wall of the cup.

2. In combination with a cup having an upwardly and outwardly flaring side wall, a concave saucer for receiving the cup and provided with an outwardly flared and upwardly extending annular rim spaced circumferentially outward from the side wall of the cup and forming an acute angle therewith, and an individual creamer comprising a container open at the top and having connected side walls and a base supported at its forward end upon the interior of the saucer adjacent the bottom of the cup and adjacent its outer end upon the rim of the saucer, one of said side walls being disposed at an acute angle with the base and substantially conforming to and bearing against the upwardly and outwardly flaring side wall of the cup with the side wall and base of the container wedged between the side wall of the cup and the rim of the saucer whereby the container is held firmly in position and the liquid contents of the container is held against spillage.

3. An individual creamer comprising a container for use with a cup having an upwardly and outwardly flaring side wall and a saucer having an outwardly and upwardly projecting rim spaced outwardly from the cup, said container having connected side walls providing an opening at the top and a base supported on the saucer and provided on its under-surface with an arcu-

ate groove for conformably receiving the outer circumference of the rim of the saucer, one of said side walls being upwardly and outwardly inclined at an acute angle with the base and substantially conforming to the upwardly and outwardly flaring side wall of the cup whereby the creamer, when placed on the saucer with the upwardly and outwardly inclined side wall of the container in contact with the adjacent side wall of the cup, is held securely upon the rim and wedged between it and the exterior side wall of the cup.

4. In combination, a saucer having a flat central portion and an annular marginal portion extending outwardly and upwardly therefrom, a cup seated upon said central portion of the saucer, and a flat bottomed jug supported upon the upper face of the marginal portion of the saucer and provided with a side face extending upwardly from its base, said face having a surface contour conforming to the surface contour of the side wall of the cup, said jug resting against the cup with its contoured side face in surface contact with the side wall thereof.

5. In combination, a saucer having a flat central portion and an annular marginal portion extending outwardly and upwardly therefrom, a cup having its outer side surface curved circumferentially and from top to bottom seated upon

the central portion of the saucer, and a flat bottom jug supported upon the upper face of the marginal portion of the saucer and having a side face portion curved laterally and longitudinally to conform to the curvature of the side wall of the cup, said jug resting against the side wall of the cup with its curved side face portion in surface contact therewith.
